COMBINED CONCRETE AND WOODEN
BENCH

Nicholas B. Boller, Los Angeles, Calif.

Application September 4, 1934, Serial No. 742,594

5 Claims. (Cl. 155—191)

My invention relates to benches or seats of the type used on lawns, in parks and the like and the principal objects of my invention are, to generally improve upon and simplify the construction of the existing forms of lawn or park benches, to provide a bench having end frames formed of concrete or the like, with seat and back panels formed of wood or the like and further, to provide a bench of the character referred to that is relatively strong and rigid in structure, having a marked degree of stability and resistance to strains and stresses that tend to break or disconnect the parts that are associated to produce the bench.

Further objects of my invention are, to construct the seat back supporting uprights so that they have a strong and substantial bearing upon the rear portions of the concrete end frames, further, to provide simple and efficient means for mounting the seat panel upon the upper portions of the concrete end frames and further, to provide a bench or seat that presents a neat and finished appearance.

With the foregoing and other objects in view my invention consists in certain novel features of construction and arrangements of parts that will be hereinafter more fully described and claimed and illustrated in the accompanying drawing in which:

Fig. 1 is a perspective view of a bench constructed in accordance with my invention.

Fig. 2 is an enlarged vertical cross section taken on the line 2—2 of Fig. 1.

Fig. 3 is an enlarged horizontal section taken on the line 3—3 of Fig. 2.

Fig. 4 is a perspective view of the lower portion of one of the uprights that are secured to the rear portions of the concrete end frames and which support the seat back.

Fig. 5 is a fragmentary perspective view of the upper rear portion of one of the concrete end frames and showing a cushioning strip of wood imbedded in the upper portion of the horizontal member of the end frame.

Fig. 6 is an enlarged vertical section taken on the line 6—6 of Fig. 2.

In the construction of my improved bench, I employ a pair of end frames that are cast or formed of concrete or analogous cementitious material, which end frames are practically identical in construction but made in rights and lefts and each end frame comprises a horizontally disposed lower rail 10, a horizontally disposed upper rail 11, a front member 12 and a rear member 13.

The end portions of the lower rail 10 are ex-

tended downward as designated by 14, in order to form feet that rest directly upon the ground or pavement.

Front and rear members 12 and 13, which connect and are integrally formed with the horizontal members 10 and 11 diverge upwardly and the upper portions of the front faces of the front members 12 are provided with flat faces 15 that occupy vertical planes.

Formed integral with the inner faces of the rear frame members 13, adjacent to the rear edges thereof, are flanges 16, the front faces 17 of which constitute elongated bearing surfaces for the lower portions of the uprights that carry the seat back panel or panels.

The lower portions of the flanges 16 are carried downward on the rear inner faces of the lower horizontal members 10 so as to increase the width or thickness of the feet 14 that are formed at the rear ends of said lower members 10. This increased thickness is designated by the numeral 18, Fig. 2.

The upright members 19 that support the seat back panels, are preferably formed of wood and their lower portions are cut away to form depending extensions 20, which are smaller in cross section than the main bodies of the uprights and these extensions are positioned immediately against the inner faces of the upright members 13 of the end frames with the rear faces 21 of said extensions bearing against the front faces of the flanges 16.

The cutting away of the lower portions of the uprights 19 to form the extensions 21, provide substantially L-shaped shoulders 22 that bear directly upon the upper surfaces of the rear members 13 and the flanges 16 that are formed integral therewith.

The uprights 19 are rigidly secured to the rear members 13 of the end frames by horizontally disposed bolts 23 that pass through the rear members 13 and through the depending extensions 21 of the uprights 19 (see Fig. 3).

Thus each upright is rigidly secured to the rear member of one of the end frames and as the rear and outer face of each extension has direct contact respectively with the front face of flange 16 and adjacent inner face of the rear member 13 and the shoulder 22 has direct bearing on the upper surfaces of the rear member 13 and flange 16, a very strong, rigid and substantial connection is provided between the uprights and the concrete end frames, which connection effectively resists breakage or splitting of the uprights in the

event that the bench is tipped over rearwardly or is dropped on a relatively hard surface.

Suitably secured to the front faces of the upper portions of the uprights 19, preferably by means of nails, screws or bolts, are one or more seat back panels such as 24. These seat back panels are preferably formed of wood.

Connecting the intermediate portions of the lower horizontal members 10, is a rail 25, preferably of wood, which functions as a connecting brace between the lower portions of the concrete end frames and the ends of this rail are suitably connected to members 10, preferably by means of bolts 26 that extend downwardly through said rails 10.

Imbedded in the upper portions of the horizontally disposed top rails 11 of the end frames, are cushioning strips 27, preferably of wood, which serve as supports for the seat panel 28.

I prefer to arrange these cushioning strips so that their upper surfaces occupy a plane a fraction of an inch above the upper surfaces of the rails 11, in order that when the seat panel is properly applied, its under-surface will not rest directly upon the concrete, of which the end frames are formed.

The seat panel 18 is rigidly connected to the cushioning strips 27 and to the top rails 11 by means of vertically disposed bolts 28 that extend downwardly through the seat panel, the cushioning strips and rails 11 (see Fig. 6).

A narrow panel 29, preferably of wood, provides an apron for the front edge of the seat, the end portions of which apron bear directly against the flat upper front faces 15 of members 12 and the upper portion of this apron is rigidly secured to the front edge of seat panel 18, preferably by means of nails or screws.

In some instances, it may be found desirable to arrange the concrete end frames so that the flanges 16 are outwardly pressed and thus when the parts of the bench are properly assembled the uprights 19 are positioned on the outer faces of the rear members 13 of the end frames instead of on the inner faces thereof, as herein shown and described.

Where the lower portions of the uprights are applied to the inner faces of the concrete end frames against the front faces 17 of the flanges, the entire lower portions of the uprights are protected from being hit by passing objects and thus the period of usefulness or service of the bench is materially increased.

The shoulders 22 on the uprights bearing directly on the upper surfaces of rear members 13 and flanges 16 removes to a considerable extent the transmission of strains delivered to the bolts 23 as a result of downward pressure on the upper portions of the uprights and as a result splitting and consequent dislodgment of the uprights from the concrete end frames is prevented. This resistance to downward movement that might be imparted to the uprights 19 is enhanced by the bearing of the lower ends of the extensions 21 upon the upper portions of the increased thickness 18 at the rear ends of lower members 10.

The increasing of the thickness of the feet at the rear lower corners of the end frames provides larger bearing surfaces for the rear portions of the end frames of the bench where the same is placed on relatively soft ground and thus counter-acting any tendency of the rear portion of the bench to sink into the ground and tip backwardly.

Inasmuch as the lower portions of the uprights bear against the inner faces of the rear members

13 of the concrete end frames and the bolts 23 that connect said uprights to the end frames, are horizontally disposed, any horizontal strains applied to either end of the bench and particularly to the back panels 24, will be transferred directly to the bolts which occupy planes parallel with the impressed strains and as a result any tendency of the uprights to split at the points where they are attached is minimized.

The advantage in producing the concrete end frames in rights and lefts is that when strains are applied to the back panels of the bench from either end horizontally, such strains will not be transferred to both uprights since said uprights have their outer faces bearing against the inner surfaces of the end frames and as a result the strains are first absorbed by the rear leg of the end frame adjacent the point or end from which the strains are applied.

The imbedding of the cushioning strips 27 in the upper portions of the upper rails 11, tends to prevent splitting of said cushion strips and consequently minimizing the development of weakness between the seat panels and the parts that are connected.

Thus it will be seen that I have provided a combined concrete and wooden bench that is relatively simple in construction, inexpensive of manufacture, having great strength and durability and which bench is very effective in performing the functions for which it is intended.

It will be understood that minor changes in the size, form and construction of the various parts of my improved combined concrete and wooden bench may be made and substituted for those herein shown and described without departing from the spirit of my invention, the scope of which is set forth in the appended claims.

I claim as my invention:

1. In a bench, the combination with a pair of 40 concrete end frames, each having a front leg and a back leg and an inwardly presented flange formed on the inner face of each back leg, which flange is substantially half the width of the back leg so as to provide a forwardly presented shoulder, of a pair of uprights constituting upward extensions of said back legs, the lower portion of each upright being cut away to provide a depending extension that fits against the inner face of each back leg and against the front face of 50 the flange thereon, there being a shoulder formed between the extension and the upper portion of the upright, which shoulder rests on top of the back leg to which the upright is applied, and fastening means passing transversely through the 55 extension and through the back leg in front of the flange thereon.

2. In a bench, the combination with a pair of concrete end frames, each having a front leg and a back leg and an inwardly presented flange 60 formed on the inner face of each back leg, which flange is substantially half the width of the back leg so as to provide a forwardly presented shoulder, of a pair of uprights constituting upward extensions of said back legs, the lower portion of each upright being cut away to provide a depending extension that fits against the inner face of each back leg and against the front face of the flange thereon, there being a shoulder formed 65 between the extension and the upper portion of the upright, which shoulder rests on top of the back leg to which the upright is applied, fastening means passing transversely through the extension and through the back leg in front of the 70 flange thereon.

flange thereon and a seat back panel secured to the uprights above said end frames.

3. In a bench, the combination with a pair of concrete end frames, each having a front leg and a back leg and an inwardly presented flange formed on the inner face of each back leg, which flange is substantially half the width of the back leg so as to provide a forwardly presented shoulder, of a pair of uprights constituting upward extensions of said back legs, the lower portion of each upright being cut away to provide a depending extension that fits against the inner face of each back leg and against the front face of the flange thereon, there being a shoulder formed between the extension and the upper portion of the upright, which shoulder rests on top of the back leg to which the upright is applied, fastening means passing transversely through the extension and through the back leg in front of the flange thereon, a seat back panel secured to the uprights above said end frames and a seat panel secured to the upper portions of said end frames.

4. In a bench, the combination with a pair of concrete end frames, each having a front leg and a back leg and an inwardly presented flange formed on the inner face of each back leg, which flange is substantially half the width of the back leg so as to provide a forwardly presented shoulder, of a pair of uprights constituting upward extensions of said back legs, the lower portion of each upright being cut away to provide a depending extension that fits against the inner face of each back leg and against the front face of the flange thereon, there being a shoulder formed between the extension and the upper portion of

the upright, which shoulder rests on top of the back leg to which the upright is applied, fastening means passing transversely through the extension and through the back leg in front of the flange thereon, a seat back panel secured to the uprights above said end frames, a seat panel secured to the upper portions of said end frames and an apron secured to the front edge of said seat panel and disposed in front of the upper portions of the front legs of the end frame. 10

5. In a bench, the combination with a pair of concrete end frames, each having a front leg and a back leg and an inwardly presented flange formed on the inner face of each back leg, which flange is substantially half the width of the back leg so as to provide a forwardly presented shoulder, of a pair of uprights constituting upward extensions of said back legs, the lower portion of each upright being cut away to provide a depending extension that fits against the inner face of each back leg and against the front face of the flange thereon, there being a shoulder formed between the extension and the upper portion of the upright, which shoulder rests on top of the back leg to which the upright is applied, fastening means passing transversely through the extension and through the back leg in front of the flange thereon, a seat back panel secured to the uprights above said end frames, a seat panel secured to the upper portions of said end frames, 20 an apron secured to the front edge of said seat panel and disposed in front of the upper portions of the front legs of the end frame and a rail connecting the lower portions of said end frames. 25
